UNITED STATES PATENT OFFICE.

JUDSON W. INGALSBE, OF ONAGA, KANSAS, ASSIGNOR OF ONE-HALF TO
CHARLES GREEN, OF WHEATON, KANSAS.

TIGHTENING DEVICE FOR DRUMS.

SPECIFICATION forming part of Letters Patent No. 635,856, dated October 31, 1899.

Application filed March 31, 1899. Serial No. 711,316. (No model.)

To all whom it may concern:

Be it known that I, JUDSON W. INGALSBE, a citizen of the United States, residing at Onaga, in the county of Pottawatomie and State of 5 Kansas, have invented a new and useful Tightening Device for Drums, of which the following is a specification.

My invention relates to tightening devices for drums of that class which employ two 10 skins or heads, known to the art by the technical name of "batter-heads" and "snare-heads," respectively.

It is not new in the art to provide tightener devices arranged for operation to strain the 15 two heads independently of each other, and while this is a very desirable feature the separate adjustment of the heads involves considerable time, because each tension device must be operated twice.

20 The object of the present invention is to provide an improved tension device capable of adjusting the drum-heads separately to secure the desired tension on the batter-head independently of the adjustment of the snare-head; but at the same time my tension device is adapted for adjustment to strain both drum-heads at one and the same operation after the heads shall have been separately placed under the desired tension, whereby slack in the 25 30 heads due to atmospheric changes and other causes may be taken up without involving disturbance of the tension of the two heads with respect to each other.

A further object of the invention is to provide an improved tension device which may be secured firmly to the drum-shell in a manner for the operating elements to be retained securely in place, and which shall, furthermore, be simple in construction and easy of 35 40 adjustment.

To the attainment of these ends the invention consists in the novel combination of elements and the construction and arrangement of parts, which will be hereinafter fully described and claimed.

45 To enable others to understand the invention, I have illustrated the preferred embodiment thereof in the accompanying drawings, forming a part of this specification, and in 50 which—

Figure 1 is a perspective view of a drum

with my tightener devices applied thereto. Fig. 2 is a vertical sectional view, on an enlarged scale, through a part of the drum and illustrating the tightener more clearly. Fig. 55 3 is a transverse section on the plane indicated by the dotted line 3 3 of Fig. 2. Fig. 4 is a detailed perspective view of the parts of the tightener detached or separated one from the other. Fig. 5 is a detailed view of 60 the wrench which may be used for adjusting the tightener.

The same numerals of reference are used in all the figures in the designation of identical parts.

65 In order that others skilled in the art may understand the invention, I have illustrated an ordinary drum by Figs. 1 and 2 of the drawings, in which a shell is indicated by the numeral 10, the batter-head and snare-head 70 by 11 and 12, respectively, and the rims by 13 and 14. These elements are all ordinary in the art and no novelty therefor is set up in this application. The rims 13 and 14 of the two drum-heads are connected by a plurality 75 of tension devices which are disposed outside of the shell 10. The improvement in the present case resides in the novel construction and adaptation of these tension devices, and I will now proceed to describe one of said tension devices, it being understood that the following description is applicable to each of the series of tension devices.

80 The base-plate 15 is applied in vertical position to the outside of the shell 10 at a point 85 between the rims 13 14, said base-plate being provided in its outer or exposed face with transverse grooves 16, that constitute seats for a pair of supporting-jaws. A clamping-plate 17 is fitted against the inner surface of the 90 drum-shell in a position opposite to the base-plate. The supporting-jaws 18 are provided with foot-flanges 19, which are fashioned to fit snugly in the seat 16 of the base-plate, and these jaws are, furthermore, provided with 95 threaded sockets 20. The base and clamping plates 15 17 and the jaws 18 are secured firmly to the shell by means of screws 21, which pass through registering apertures 22, formed in the clamping-plate, the drum-shell, 100 and the base-plate, and these screws engage with the threads in the sockets 20 of the jaws

18. The heads of the screws bear against the clamping-plate 17, and said screws serve to draw the jaws 18 firmly against the base-plate 15, whereby the several parts are clamped 5 firmly to the shell 10.

A revolute sleeve 23 is provided at one end with a polygonal head 24, and the opposite end of this sleeve is threaded internally with a right-hand female thread 25. A companion 10 sleeve 26 is provided with a similar head 27 and with a left-hand female thread 28. Between the contiguous heads of the two revolute sleeves 23 26 is interposed a bearing-plate 29, which is secured firmly to the base-plate 15, and this bearing-plate is provided with an angular or square aperture 30. The sleeves 23 26 are cylindrical except for the polygonal heads 24 27 on their adjacent ends, and said sleeves are fitted loosely in transverse openings 33, which are provided in the pair of jaws 18. The function of the bearing-plate 29 is to support a connecting pin or arbor 31, which is fitted or attached to the plate 29 and is extended into the heads and the sleeves. 20 25 This connecting-pin 31 is cylindrical except for a square central boss 32, the contour and dimensions of which correspond to the hole 30 of the bearing-plate.

By reference to Fig. 2 it will be seen that 30 the bearing-plate 29 is supported on the plate at a point midway between the jaws 18 and that the sleeves 23 26 are fitted loosely in the openings of the jaws and for the polygonal heads 24 27 to lie on opposite sides of the bearing-plate. The heads of the two sleeves are thus arranged contiguous one to the other, but are separated by the bearing-plate, and each sleeve is confined against endwise movement on the supporting device formed by the 35 plate and the jaws, owing to the fact that one end of the polygonal head abuts against one jaw and the opposite end of said head impinges against the supporting-plate. The function of the connecting-pin 31 is to furnish 40 an internal support for the sleeves in order to maintain them in alinement and prevent said sleeves from assuming canted or tilted positions, said connecting-pin being itself supported in place by the bearing-plate. The 45 alined sleeves are thus mounted in the jaws to rotate freely therein independently one of the other, and each sleeve is restrained from endwise movement.

The independently-adjustable sleeves 23 26 50 receive the inner ends of the tension-rods 34 35, respectively. One of the rods is provided with a right-hand male thread to screw into the similarly-formed thread of one of the revolute sleeves; but the other rod is provided 55 with a left-hand male thread adapted to be screwed into a like female thread of the other sleeve. The rod 34 is provided with a hook 36, adapted to clasp the rim 13; but the other rod 35 has a hook 37 to clasp the rim 14.

60 From the foregoing description, taken in connection with the drawings, it will be understood that the sleeve 23 of each tension de-

vice may be rotated in its support in one direction to draw the rod 34 inwardly for the purpose of making its hook adjust the rim 13, and as each tension device may have its sleeve 23 operated as described the rods 34 are adapted to draw or strain the batter-head 11 independently of any adjustment of the snare-head 12. In like manner the sleeves 26 75 of the tension devices may be rotated to adjust the rods 35 for the purpose of drawing the rim 14 inwardly to adjust the snare-head 12, and this adjustment of the snare-head is effected without disturbing the tension of the 80 batter-head.

One of the salient features of my invention is the adaptation of the tension devices to have their sleeves 23 26 adjusted simultaneously, and this end is attained by disposing 85 the polygonal heads 24 27 of each pair of sleeves 23 26 contiguous to each other in order that the two sleeves 23 26 may be rotated simultaneously by a suitable implement for the purpose of drawing the right and left 90 threaded rods 34 35 inward toward each other at one operation.

As a suitable means for adjusting the sleeves 23 26 individually or simultaneously, I have provided a wrench 38. (Illustrated by 95 Fig. 5 of the drawings.) This wrench consists of a bar or shank having a narrow jaw 39 at one end thereof, and the other end of this bar or shank is formed with a wide jaw 40, which is adapted to span the bearing-plate 29 and 100 to engage with the heads 24 27 of the two sleeves. The wrench may be used to adjust either sleeve 23 or 26 by fitting the narrow jaw 39 to the head of the proper sleeve and manipulating the wrench to turn the sleeve, 105 it being understood that the wrench may be applied to the head of either sleeve 23 or 26. In order to adjust the sleeves 23 26 of the tension device simultaneously, the operator reverses the wrench 38 to bring its wide jaw 40 110 into position for use, and this jaw may be fitted to the tension device in a position to span the bearing-plate 29 and engage with the contiguous heads 24 27 of the two sleeves 115 23 26. By turning the wrench in a proper direction the sleeves 23 26 may be turned for equal distances simultaneously, and the rods 34 35 are thus adapted to be drawn inwardly 120 in order to strain the batter and snare heads at one operation.

Changes in the form, proportion, size, and the minor details of construction within the scope of the appended claims may be resorted to without departing from the spirit or sacrificing any of the advantages of this invention. 125

What I claim is—

1. A tension device for drums consisting of the revolute coupling-sleeves arranged in alinement with each other, and right and left threaded rods connected separately to said 130 coupling-sleeves, the latter being supported in alinement with each other, substantially as described.

2. A tension device for drums consisting of

the independently-revoluble sleeves having right and left hand threads, the right and left threaded adjusting-rods screwed separately in said sleeves, and means for supporting the sleeves in alinement with each other, whereby the sleeves may be turned collectively or individually, as set forth.

3. A tension device for drums consisting of the independently-revoluble threaded sleeves, 10 the right and left threaded rods screwed into said sleeves, and a connecting-pin supported independently of the sleeves and engaging therewith, substantially as described.

4. A tension device for drums consisting of 15 a base-plate, jaws supported thereon, threaded revoluble sleeves mounted in said jaws and having the polygonal heads at their contiguous ends, the right and left threaded rods screwed separately into the sleeves to be 20 adjusted thereby, and means for retaining the sleeves in alinement with each other, substantially as described.

5. A tension device for drums consisting of 25 a base-plate provided with a bearing-plate, jaws clamped to said base-plate on opposite

sides of the bearing-plate, the threaded revoluble sleeves mounted in said jaws and having the polygonal heads confined between the jaws and the bearing-plate, a connecting-pin supported in the bearing-plate and extending into the sleeves, and the threaded rods screwed separately into the sleeves, substantially as described. 30

6. A tension device for drums consisting of a base-plate having the transverse seats, a 35 clamping-plate, screws passing through the clamping and base plates and connected to the jaws to hold the parts firmly together, the revoluble sleeves mounted in the jaws and provided with the polygonal heads at their 40 contiguous ends, and the threaded rods screwed separately into the sleeves, substantially as described.

In testimony that I claim the foregoing as my own I have hereto affixed my signature in 45 the presence of two witnesses.

JUDSON W. INGALSBE.
